UNITED STATES PATENT OFFICE.

WILLIAM RICHARD WHITE, OF BLOOMINGTON, ILLINOIS.

GATE.

SPECIFICATION forming part of Letters Patent No. 593,146, dated November 2, 1897.

Application filed October 16, 1896. Serial No. 609,131. (No model.)

To all whom it may concern:

Be it known that I, WILLIAM RICHARD WHITE, a citizen of the United States, residing at Bloomington, McLean county, State of Illinois, have invented certain new and useful Improvements in Gates, of which the following is a specification.

This invention relates to certain new and useful improvements in swinging gates; and it consists, substantially, in such features of construction, arrangement, and combinations of parts as will hereinafter be more particularly described.

The invention has reference more particularly to that class of swinging gates which are opened and closed through the medium of hand-levers mounted or fulcrumed upon supporting-posts suitably disposed or arranged on one side of the roadway; and the object of the present invention is the improvement of the gate generally, but more particularly the connections between the inner ends of the operating-levers and the devices by which the latch-bar is automatically opened and closed upon the application of a force applied to the hand-levers.

The invention also has certain other objects in view, all as will more fully hereinafter appear when taken in connection with the accompanying drawings, wherein—

Figure 1 is a view in perspective of a swinging gate constructed and arranged in accordance with my present invention; and Fig. 2 is a top or plan view, the full lines indicating the closed position of the gate and the dotted lines the open position thereof. Fig. 3 is an enlarged view, in front elevation, of the laterally-projecting frames on the gate, together with a portion of the gate and the supporting-post therefor. Fig. 4 is a detail view, in part section, representing more clearly the construction and arrangement of the movable lever connection by which the latch-bar of the gate is operated. Fig. 5 is a detail of a modification.

In its general appearance the swinging gate herein shown and about to be described bears a somewhat close resemblance to some of the former Letters Patent which have been granted me on the subject—namely, the one granted to me on the 22d of August, 1893, No. 503,887; but it will be found from the de-

scription hereinafter following that the present invention differs materially in several respects.

The present invention is capable of a great many different embodiments, and it will be understood that I am not limited to the precise details of construction and arrangement shown, although in practice I have found the present embodiment to possess very marked advantages, and therefore I prefer its use for all general purposes.

Thus, as shown in the drawings, 1, 2, and 3 designate supporting-posts arranged along side of the roadway, the latter being the post to which the gate is hinged and the central post being the one which carries the guide for the inner connected ends of the hand operating-levers. These said levers A B are mounted or fulcrumed, respectively, at *a* and *b*, the one directly upon the post 1 and the other upon a strut or brace 4, connecting with the end of a horizontal beam 5, extending parallel with the roadway and supported at 75 a height somewhat above that of the gate by means of the said posts 1, 2, and 3, already mentioned.

The inner ends of the operating-levers A and B could be connected to be operated in unison in many different ways; but I have found considerable advantage resulting in the special connections therefor which will be more specifically referred to hereinafter. Disposed on the opposite side of the roadway in direct alinement with the post 3 is another post 6, and this latter post has projecting from its face a suitable catch 7, having a beveled or rounded edge 8 and formed with a shoulder 9, around which the engaging portion of the latch-bar passes, as will hereinafter appear. The gate itself is preferably a metallic gate, (indicated at C,) and this gate is mounted or supported upon the post 3 by means of metallic loops or hinges *c c*, fastened in the said post, and the post is provided with a series of openings 10 to receive the hooked end 11 of a bracket 12, which has vertical movement upon the upper loop or hinge, and it is through the medium of this bracket that the gate may be adjusted vertically on its hinged supports, so as to carry the lower edge of the gate nearer to or farther from the surface of the ground; but no

specific mention need herein be made of the bracket, since the same is already covered by me in a former Letters Patent. For the purposes of lightness and strength the said gate 5 C is constructed of channel-metal portions e, extending its entire length, and these portions are united by flat vertical portions f and diagonal bracing portions g, while the remainder of the gate is constituted of a number 10 of metallic rods passing through the said vertical and diagonal portions and suitably secured in place. This general construction of gate has been shown by me in a former Letters Patent, in which is shown also a 15 somewhat similarly constructed latch-bar movably supported by the gate. In the present instance the said latch-bar D at its forward end is bent into a doubled right-angled portion m, adapted to engage the shoulder of 20 the catch 7, projecting from the side of the post 6. Considerable attention has been heretofore paid both by myself and others to the devices for operating somewhat similarly disposed latch-bars by which to relieve the said 25 bars of all strain as well as to cause the same to be instantly affected upon the application of force to either one of the operating hand-levers. In my former patent, already referred to by number, the movable latch-bar is 30 released from its catches by means of a rocking arm; but while the said arm has been found extremely advantageous it is desirable that all strains be distributed in right lines and that the gate itself rather than the devices or 35 connections which operate the latch-bar be made as much as possible to bear them. The present construction has been found to meet all these requirements as well as to be far more simple in other respects.

40 Thus E represents as a whole a laterally-projecting frame supported by the gate, in the present instance comprising the substantially horizontal portion 15, having the side portions 16 and 17 secured at 18 and 19, preferably to one of the metallic rods of the gate, the said horizontal portion 15 being substantially in the same horizontal plane as the longer portion of the movable latch-bar, and except for the reasons about to be stated the 45 said horizontal frame need not embody further elements or additions. Supported about centrally of the horizontal portion of the said laterally-projecting frame is a movable or oscillating lever F, which, as shown, 50 is provided at one end with a pin 18', passing loosely into an eye 19', formed or provided on the latch-bar. At its other end the said lever is turned over or bent upward at 20 to constitute a vertically-disposed lug or ear 21, 55 having an opening 22, in which is loosely held the lower end of the connecting-bar G, the opposite or upper end of which is similarly supported in an eye 22', secured in the 60 underside of the hand-lever B a short distance 65 from the inner end of the said lever. The said movable or oscillating lever F turns or oscillates upon a pin or screw 25, passing

through the horizontal portion of the said laterally-projecting frame, and from the construction and arrangement thus far described 70 it will be seen that simply to pull upon either one of the hand-levers A or B would impart to the said lever F a movement sufficient to disengage or release the latch-bar, and thus permit the gate to be swung open or closed, 75 the connecting-bar between the hand-levers and said lever F being first slightly elevated and then swung to an opposite position, as shown in Fig. 2, the arrangement of parts 80 being such that the gate will be carried to either position by its own momentum and without encountering a dead-center. While, as I have stated, such a construction as I have described up to this point could be made to answer many of the requirements of an ordinary swinging gate of this character, it is 85 obvious that all the strain would have to be borne by the lever connection F between the lower end of the connecting-bar G and the connection with the latch-bar, or at least 90 practically so, and therefore to obviate this and to cause all of the strain to be either directly or indirectly borne by the gate itself I resort to the construction about to be described.

95 Thus H represents an auxiliary laterally-projecting frame supported at its ends upon one of the longitudinal bars of the gate or on the uprights thereof, being preferably oval or semicircular in its shape and being riveted or otherwise secured at 30 to the side portions 16 and 17 of the said laterally-projecting frame E. It will be noticed that the said auxiliary frame H is turned upward at the front in such manner as to be substantially 100 slightly above the horizontal portion 15 of the main laterally-projecting frame E, which is for the purpose of carrying the parts of both of the frames, as well as the movable connections for the latch-bar, as far beyond the reach of stock as possible. If intended for 105 no other purpose, this auxiliary frame H would materially strengthen the frame E; but it is intended to subserve the additional function about to be described. Thus it will be 110 observed that at a point coinciding with the end of the lever F, connecting with the lower end of the connecting-bar G, the said auxiliary frame H is notched or slotted at 35 to receive 115 the tongue or end 36, formed with or carried by the said lever F, and in this way not only is all lateral strain taken from the movable latch-bar, but such strain is made to be more or less directly borne by the gate structure 120 itself. For instance, as heretofore devised in 125 many instances, and I might also say the same to be the case with the rocking arm of my former Letters Patent referred to, not only has the latch-bar had to subserve its function as such in holding the gate to its desired 130 positions, but it has also had to practically sustain the necessary strain required to swing or turn the gate upon its hinges. This is not the case in the present instance, since there

is practically no lateral strain upon the latch-bar, while all strain is borne by the lateral frames E and H in such manner as to be imparted almost directly to the gate itself.

5 When either one of the hand-levers is operated to open or close the gate, the first effect is to slightly move or oscillate the lever F upon its pivot in the horizontal portion 15 of the frame E, and this movement of the said lever F is imparted to the latch-bar. Inasmuch, however, as the movement of the said lever F is limited by the slot or notch 35 in the projecting portion of the auxiliary frame H as soon as the said lever F has moved the latch-bar the strain or moving force upon the gate itself is immediately received by the auxiliary frame, since the tongue 36 of the lever F comes into contact therewith at one or the other extremity of the slot 35, accordingly as the gate is operated to be opened or to be closed. It will thus be seen that no lateral strain is thereafter exerted on the latch-bar or on the operating-lever F, and also that no other strain is exerted on either of these parts except such only as is required to move the latch-bar back and forth in a direct line. By increasing or diminishing the length of the slot or notch 35 in the auxiliary frame H the degree of movement of the latch-bar may 30 be adjusted or varied to suit different requirements, and in order that these changes may be effected without much trouble I preferably in the first instance make the slot or notch 35 a little longer than is absolutely required, and then I insert in one end or the other of the said slot a wedge or key 40, against which the tongue 36 of the lever F impinges. The adjustment or regulation of the movement of the latch-bar can thus be 40 had either by the insertion of wedges or keys of different thicknesses, so as to limit the movement of the lever F, or else the said key might be made capable of adjustment in the slot and held at different positions therein by any suitable means.

While I have herein shown and described a particular form of latch-bar as well as a particular shape of the portion thereof which engages with the catches on the posts 1 and 5, it is evident that I am not restricted to such form of latch-bar, and instead of using the right-angled engaging portion at the forward end thereof I might use a tapered form of engaging portion, or else such engaging portion might be of a T shape, and in fact I am not limited to any special form of locking or engaging portion for the bar so long as the said bar is engaged or released on imparting thereto a longitudinal movement through the 60 medium of devices connected with the operating-levers.

The inner ends of the operating-levers A and B are of course movably connected, so that the two will be operated upon the application of a force to either, and it is desirable that there shall be no lost motion between these levers and consequently the other parts

of the gate, and I have found a convenient form of connection in the general construction and embodiment which I have shown 70 herein. Thus, for instance, the lever A is formed with a slot at its end, in which is received and held in place by means of suitable rivets or pins 46 a lifting-arm 47, disposed at a slight angle forward of the end of the said lever A and having an opening 48, in which is held a link or yoke 49, which embraces the corresponding end of the opposite hand-lever B and has a working movement upon a pin or rivet 50, passing all the way through the 80 said lever B from side to side. It will be seen that while the said link or yoke 49 embraces the two sides of the lever B it also extends up a suitable distance beyond the top of said lever to enable the end of the lever to have a 85 free movement as it is carried upward by the operation of opening and closing the gate, and, furthermore, in order to prevent any undue lateral movement between the lifting-arm and the said link or yoke the latter is 90 contracted at the point of its movable connection with the said lifting-arm, as shown at 51, for instance. By this form of connection it will be seen that the levers A and B operate in unison and that as soon as one is 95 operated there is a lifting action imparted to the other, and the momentum of the gate is always sufficient to restore the said levers to their normal positions after once being elevated or raised at their inner ends. These 100 levers are also prevented from lateral movement relative to each other, except such as is required for freedom of action, and relative to their fulcrums are maintained in their operative positions by means of the vertically- 105 arranged loop-guide 55, carried by the central post 2, hereinbefore referred to.

It is thought the construction and arrangement of the parts of my present invention will be fully understood, and it is of course 110 unnecessary for me to state that my improved main and auxiliary laterally-projecting frames could be employed also with equal effect upon a wooden gate, the said frames E and H, however, being preferably of metal, 115 as well as the operating devices with which they co-operate. I have referred to the auxiliary frame as being curved or semicircular in shape, but it is evident that the same could be of any other form desired, as could also 120 the frame E and its adjuncts.

As shown in the modification Fig. 5, the lug or projecting portion 60, which corresponds to the part 21 in the remaining figures, is carried upward practically to a level with 125 the top of the gate, while in other respects the construction of the oscillating lever F is the same. By so extending the portion 60 I am enabled to use a much shorter connecting-bar G, and, besides, there is less liability of 130 the gate being opened and closed through the efforts of stock.

While I have defined a specific form of pivoted oscillating lever F, it is evident, of course,

that I am not restricted thereto, since the said lever is capable of a great many different constructions, and instead of its being a straight lever it may be a lever comprising one or more bends or turns, and in fact the construction of this lever may be modified in various ways, as may be the connections therewith of the latch-bar and the connecting-bar from the hand-levers. In other words, as distinguished from former inventions the said lever is pivoted substantially at its central part to oscillate or swing in a horizontal plane, and it is evident that such a lever could be utilized in various forms, and also instead of being flat can be readily made of round rod metal. It may be added that the movable latch-bar is provided with an adjustable nut 75, which enables the bar to be so adjusted as to conform the engaging portion thereof to different sizes and forms of catches to receive the same, and also in order to limit the outward or forward movement of the said latch-bar the end thereof projecting beyond that part of the gate adjacent to the hinges is provided with a head 76, and it will thus be seen that the latch-bar possesses advantages also in this particular respect. It will be seen that the position and relative arrangement of the parts is such that normally when the gate is closed the latch-bar is in a retracted position to engage the shoulder of the catch-plate projecting from the post 6 and that when the gate is opened and the latch-bar engaged by the catch on the post 1 the said latch-bar is in a projected position relative to the gate. This arrangement is clearly illustrated in Fig. 2, wherein it will be seen that the outer end of the oscillating lever F, which connects with the lower end of the connection-bar, is normally in a forward position relative to its pivotal point, the opposite end of the lever which is in movable connection with the latch-bar being in a position slightly nearer to the hinged or inner end of the gate. Thus when either one of the operating-levers is depressed at its outer end the outer end of the oscillating lever is drawn backward or in the direction of the said operating-levers, while the inner end of the said oscillating lever is carried forward, and consequently the latch-bar is moved forward and is released. This result can be effected in many different ways, and it is apparent that I am not limited to the particular devices herein shown for accomplishing the same. For instance, the oscillating lever F might be mounted on a simple projection from the side of the gate, and while such projection would constitute substantially a lateral frame it need not be literally a frame in the sense employed in some of the other connections herein referred to.

Without limiting myself to the precise construction shown and described, I claim as my invention—

1. In a swinging gate, the combination with pivoted operating-levers therefor, of a con-

nection between the adjacent ends of the levers comprising a fixed upwardly-extending lifting-arm on one lever and a movable link on the other lever, the said arm and link being movably connected at a point above the levers, substantially as described.

2. In a swinging gate, the combination with pivoted operating-levers therefor, of a connection between the adjacent ends of the levers comprising a fixed lifting-arm on one lever, inclined forward with respect thereto, a pivoted link on the other lever also inclined relative to its lever, the link and arm being movably connected, and rivets or pins for securing said arm and link to the levers, substantially as described.

3. In a swinging gate, the combination with pivoted operating-levers therefor, of a connection between the adjacent ends of the levers comprising a lifting-arm on one lever, inclined forward with respect thereto, and a pivoted link on the other lever also inclined relative to its lever, the said arm and link being movably joined together at a point above the said levers, substantially as described.

4. In a swinging gate, the combination with pivoted operating-levers therefor, of a connection between the adjacent ends of the levers comprising a lifting-arm on one lever, and a movable link on the other, the said arm and link being movably joined together, and the said link being constructed to embrace the sides of its lever and contracted at the point of its connection with said arm, substantially as shown and for the purpose described.

5. In a swinging gate, the combination with the gate and pivoted operating-levers therefor, of a longitudinally-movable latch-bar, a laterally-projecting fixed arm or frame on one side of the gate, a horizontally-movable lever supported on said lateral frame and being in direct movable connection with the latch-bar, and the connecting-bar in movable connection with the outer end of said lever and in similar connection with one of the operating-levers, substantially as described.

6. In a swinging gate, the combination with the gate and pivoted operating-levers therefor, of a longitudinally-movable latch-bar constructed at its forward end to engage catches on the posts therefor, and also provided at near its inner end with an eye, a laterally-projecting frame on one side of the gate, a pivoted horizontally-oscillating lever supported on said frame and having one of its ends entering the eye of the latch-bar, and a connecting-bar pivotally united with the outer end of said lever, and in similar connection with one of the operating-levers, substantially as described.

7. In a swinging gate, the combination with the gate and pivoted operating-levers therefor, of a movable latch-bar, a laterally-projecting frame on the gate, a horizontally-movable lever supported by the frame and in movable connection with the latch-bar and

provided with a vertically-disposed lug or projection, and a connecting-bar suspended from one of the operating-levers and in pivotal connection with said lug or projection, substantially as described.

8. In a swinging gate, the combination with the gate and pivoted operating-levers therefor, of a movable latch-bar, a laterally-projecting frame on the gate, an auxiliary frame connected to said lateral frame, an oscillating lever in direct movable connection with said latch-bar and guided in a slot in the auxiliary frame, and means for operating said lever from the pivoted hand-levers, substantially as described.

9. In a swinging gate, the combination with the gate and pivoted operating-levers therefor, of a movable latch-bar normally in a retracted position when the gate is closed, a laterally-projecting frame on the gate, an auxiliary frame connected to said lateral frame, an oscillating lever pivoted on the laterally-projecting frame and guided in its movement by the auxiliary frame, and a connecting-bar between the said lever and operating-levers for the gate, substantially as described.

10. In a swinging gate, the combination with the gate and hand operating-levers therefor, of a movable latch-bar, a main and an auxiliary laterally-projecting frame on the gate, the latter having a longitudinal slot therein, an oscillating lever pivoted to the main frame and connected with the latch-bar, and provided with a tongue moving in the slot of the auxiliary frame, and a connecting-bar between the hand-levers and the said oscillating lever, substantially as shown and described.

11. In a swinging gate, the combination with the gate and hand operating-levers therefor, of a movable latch-bar, a main and an auxiliary laterally-projecting frame on the gate, the latter having a longitudinal slot therein, an oscillating lever pivoted to the main frame and movably connected with the latch-bar, and being provided with a projection reaching to near the top of the gate as well as with a tongue moving in the slot of the auxiliary frame, and a connecting-bar pivotally connected with one of the hand operating-levers at one end and similarly connected at its other end with the projection on said oscillating lever, substantially as shown and for the purpose described.

12. In a swinging gate, the combination with the gate and a movable latch-bar thereon, of the main laterally-projecting frame, the oscillating lever pivoted thereon in movable connection with the latch-bar, the auxiliary frame having a longitudinal slot receiving the end of said lever, and provided with a key or wedge for regulating the movement of

said lever, and means for operating the said lever, substantially as shown and described.

13. The combination with the gate and operating-levers therefor, of a latch, a horizontally-oscillating lever connected to operate the latch, and in direct movable connection therewith and connected to be operated by the operating-levers, substantially as described.

14. The combination with the gate, of the movable latch-bar provided with a nut for adjusting the same, substantially as described.

15. In a swinging gate, the combination of a movable latch-bar normally in a retracted position when the gate is closed, operating hand-levers for the gate, and means or connections between the inner ends of said hand-levers and the latch-bar, whereby as the levers are operated to open the gate the said latch-bar is advanced or moved forward, substantially as shown and for the purpose described.

16. The combination with the gate, and the operating hand-levers therefor, of a movable latch-bar normally in retracted position when the gate is closed, a catch engaging the bar in this position, a connecting-bar pivotally attached to one of the operating-levers, and connections between the lower end of said bar and the latch-bar, whereby the said latch-bar is moved forward and released upon operating the hand-levers, substantially as described.

17. The combination with the gate, and the operating hand-levers therefor, of a movable latch-bar normally in retracted position when the gate is closed, and in an advanced position when the gate is opened, catches for engaging the gate in each of its positions, and connections between the said latch-bar and the operating-levers whereby the latch-bar is operated, substantially in the manner and for the purpose described.

18. The combination with the gate, and the operating hand-levers therefor, of a movable latch-bar normally in retracted position when the gate is closed, and constructed at its forward end to be engaged by a catch, a pivoted oscillating lever in movable connection with said latch-bar at or near the inner end thereof, and a swinging connecting-bar between said oscillating lever and the inner end of one of the hand-levers, substantially as described.

In testimony whereof I have signed my name to this specification in the presence of two subscribing witnesses.

WILLIAM RICHARD WHITE.
